US00D994681S

(12) **United States Design Patent** (10) Patent No.: **US D994,681 S**
Herbst (45) Date of Patent: ** Aug. 8, 2023

(54) **COMPUTER SCREEN DISPLAY OR PORTION THEREOF WITH GRAPHICAL USER INTERFACE**

(71) Applicant: **Richard Herbst**, Boynton Beach, FL (US)

(72) Inventor: **Richard Herbst**, Boynton Beach, FL (US)

(**) Term: **15 Years**

(21) Appl. No.: **29/758,351**

(22) Filed: **Nov. 13, 2020**

Related U.S. Application Data

(63) Continuation-in-part of application No. 16/230,101, filed on Dec. 21, 2018, now Pat. No. 10,839,697.

(57) **CLAIM**

The ornamental design for a computer screen display or portion thereof with graphical user interface, as shown and described.

DESCRIPTION

The FIGURE is a front view of a computer screen display or portion thereof with graphical user interface showing the new design.

The outermost broken line illustrates the computer screen display, and the broken line showing of alpha-numeric text within the outermost broken line illustrate portions of the graphical user interface. None of the broken lines form part of the claimed design.
